(57) **CLAIM**

The ornamental design for a shroud, as shown and described.

DESCRIPTION

FIG. 1 is a top perspective view of a first embodiment showing a shroud in accordance with our new design;

FIG. 2 is a bottom perspective view thereof;

FIG. 3 is a bottom plan view thereof;

FIG. 4 is a first side view thereof, the view rotated 180 degrees therefrom being a mirror image thereof;

FIG. 5 is a second side view rotated 90 degrees relative to the first side view, the view rotated 180 degrees therefrom being a mirror image thereof; and

FIG. 6 is a top plan view thereof;

FIG. 7 is a top perspective view of a second embodiment showing our new design for the shroud;

FIG. 8 is a bottom perspective view thereof;

FIG. 9 is a bottom plan view thereof;

FIG. 10 is a first side view thereof, the view rotated 180 degrees therefrom being a mirror image thereof;

FIG. 11 is a second side view rotated 90 degrees relative to the first side view, the view rotated 180 degrees therefrom being a mirror image thereof; and,

FIG. 12 is a top plan view thereof.

The broken circular lines shown in the drawings are shown for illustrative purposes only and form no part of the claimed design. In addition, the surface shading, if any, illustrated in the drawings is provided merely to highlight the contour of the design; it is not intended to be illustrative of texture, transparency, opaqueness, or gloss.
